WESTERN ELECTRIC COMPANY, INCORPORATED, A CORPORATION OF NEW YORK.

SELECTING SYSTEM.

1,171,415.

Specification of Letters Patent. Patented Feb. 15, 1916.

Application filed March 20, 1914. Serial No. 825,970.

To all whom it may concern:

Be it known that I, OSCAR A. DANIELSON, a citizen of the United States, residing at New York city, in the county of New York 5 and State of New York, have invented a certain new and useful Improvement in Selecting Systems, of which the following is a full, clear, concise, and exact description.

This invention relates to selecting systems 10 and is particularly adapted for use in printing telegraph receivers although not exclusively limited to such use, and its principal object is to provide an improved system of this type wherein one selection may be retained and another selection produced simultaneously. To this end a system with 15 electromagnetic devices for effecting the actuation of selective apparatus is provided with means for altering the circuit arrangements 20 of both the devices and the apparatus, whereby the cause and effect of their operation may overlap.

The above and other objects of this invention will be fully set forth in the following description and claims, and will be more 25 readily understood by reference to the accompanying drawing in which the system is shown diagrammatically.

The transmitting and preliminary selecting apparatus with which the system of this invention is adapted to coöperate, may be of 30 any suitable type, one such being that disclosed in Patent No. 1,086,899, dated February 10, 1914, to Oscar A. Danielson. In this 35 patent are shown means for selectively closing any one of six secondary circuits.

The six secondary selecting circuits may be represented by the six conductors 1, 2, 3, 4, 5, 6 and it is by the completion of one or 40 more of the first five and the sixth of them that a selection is accomplished. In each of the conductors 1 to 6 inclusive is a relay 11 to 16 inclusive which controls the energization of corresponding selecting devices or 45 magnets 21 to 26 inclusive. An overlap relay 30 is provided through whose armatures 31 and 32 the energizing circuit of the magnets 21 to 26 and the holding circuits of the relays 11 to 16 may be so altered that, after 50 causing the energization of certain magnets, the relays may be returned to normal and again selected without interfering with the previously operated magnets. This overlapping of functions allows of very rapid re-

ceiving and translation of signals, for one 55 signal combination may be initiating a new selection while the operation selected by the next preceding signal combination is being completed.

Whenever any of the circuits including 60 conductors 1 to 5 inclusive is completed, the corresponding relays 11 to 15 inclusive are energized by current flowing therethrough from battery 35. Thereupon the selected relays 11 to 15 attract both of their armatures, 65 the upper completing circuits for the corresponding magnets 21 to 25 from battery 40, armature 31 of overlap relay 30, upper armatures of operated relays 11 to 15, and actuating windings of corresponding magnets 21 to 25 to ground at 41. The magnets 21 to 26 inclusive are each provided with a holding winding included in a circuit from battery 45, armature of a clear-out relay 46, condactor 47 to ground 48, after passing in 70 series through all of the holding windings of magnets 21 to 26. The current flowing through this circuit is insufficient to cause magnets 21 to 26 to initiate the operation controlled by each, but is sufficient to hold 75 the magnets to their work after the energizing windings have been energized. The lower armatures of the actuated selecting relays 11 to 16 complete holding circuits therefor from grounded battery 35, windings, 80 front contacts and lower armatures of relays 11 to 16, and a back and movable contacts of magnet 26 to ground.

Certain of the selecting relays 11 to 15 and corresponding magnets 21 to 25 having 85 been actuated and held, as hereinbefore described, and whatever operations are to be controlled by magnets 21 to 25 having been initiated, the sixth circuit including conductor 6 is closed. Relay 16 attracts its armatures causing the completion of an energizing circuit for its magnet 26 and a holding circuit for itself.

Relay 26 attracts its armature 50, whereupon a circuit is completed from grounded battery 40, overlap relay 30, armature 50 and movable contact of magnet 26 to ground, causing the overlap relay 30 to attract its armatures 31 and 32. The previously traced holding circuit for relays 11 to 16 is broken 100 at the fixed and movable contacts of magnet 26, whereupon the selecting relays release 105 their armatures and return to normal ready

to receive the next selection. The operated magnets 21 to 25 and magnet 26, however, do not become inoperatively deenergized, due to the previously described holding circuit. The attraction of the armature 31 of overlap relay 30 opens the previously traced energizing circuits for the magnets 21 to 26 so that the previously selected arrangement of these magnets cannot be disturbed by a subsequent energization of relays 11 to 16, unless the first cycle is completed, when the overlap relay 30 will be deenergized.

The attraction of armature 31 of overlap relay 30 prepares a new holding circuit for the relays 11 to 16 from grounded battery 35, windings, front contact and armature of the relays 11 to 16, front contact and armature 32 of overlap relay 30 to ground.

After the completion of all of the operations initiated by magnets 21 to 26, means (not shown) causes the energization of the clear-out relay 46. The attraction of the armature of clear-out relay 46 opens the holding circuit for all the magnets 21 to 26, whereupon these magnets are completely deenergized. Relay 26 releases its armature 50, whereupon the energizing circuit for overlap relay 30 is opened and the first traced holding circuit for the relays 11 to 16 is reestablished. It is important that upon the release of armature 50, the movable and fixed contacts of magnet 26 become engaged prior to the disengagement of armature 50 and the movable contact in order that any holding circuits for relays 11 to 16 which may have been established will not be broken.

The deenergization of overlap relay 30 prepares the previously traced actuating circuits for magnets 21 to 26 so that in case a subsequent selection of relays 11 to 16 has been made, the energizing circuits of the

chosen magnets 21 to 26 will be completed simultaneously.

What is claimed is:

1. A selecting system comprising a plurality of selecting relays, a plurality of devices controlled thereby, circuits for said relays and devices, means for altering the circuit conditions of said relays and said devices so that said relays may function 45 without affecting said devices, and means for restoring the circuit conditions so that any of said relays which have so functioned may affect the corresponding said devices.

2. A selecting system comprising a plurality of selecting relays, an energizing and a holding circuit therefor, a plurality of selecting devices, actuating circuits for said devices controlled by said relays, and means for altering the circuit conditions of said 50 relays and devices and establishing new circuit conditions for said relays, whereby the operative functions of said relays and said devices may overlap.

3. A selecting system comprising a plurality of selecting relays, a plurality of selecting devices each controlled by a corresponding said relay, circuits influencing the action of said relays and cooperating with said relays and said devices, and means for 55 altering the condition of said circuits for allowing said relays to operate without affecting said devices and then cause the relays which have so operated to subsequently affect said devices.

In witness whereof, I hereunto subscribe my name this 17th day of March, A. D. 1914.

OSCAR A. DANIELSON.
